YARN WINDING MACHINE

Walter Henry Bowden, East Geelong, Australia

Application November 26, 1935, Serial No. 51,567
In Australia November 28, 1934

5 Claims. (Cl. 242—35.5)

This invention relates to machines for winding yarn on to spools or bobbins helically in layers of repeatedly changing direction.

One object of this invention is to provide a 5 yarn winding machine in which the tension on the yarn does not increase as the diameter of the spool or bobbin increases, thus obviating the risk of varying the thickness of the yarn.

A further object of this invention is to provide 10 a yarn winding machine in which chafing of yarn during its travel through moving guide means is minimized.

A still further object of this invention is to provide 15 a yarn winding machine in which the spools or bobbins are supported without the aid of holding means which would retard their removal from their supporting axles.

Another object of this invention is to provide 20 a simple and efficient yarn winding machine which occupies small floor space.

A still further object of this invention is to provide 25 a yarn winding machine which is so compact and accessible that each operator may closely supervise the winding of a large number of spools or bobbins, repair any breaks, and remove completed spools or bobbins with minimum loss of time.

An improved yarn winding machine, according to this invention, includes a drum adapted to 30 be rotated about a vertical axis, a plurality of spindles supported around the periphery of the drum at circumferentially spaced intervals in such manner that a spool or bobbin on each spindle (or yarn wound on it) contacts with and 35 is rotated by the drum, an undulating slot or groove in the said drum, a fixed vertical guide bar associated with each winding spindle supported adjacent to the drum periphery, a slipper on each said guide bar, a yarn guide on each 40 said slipper, and a projection from each slipper engaging the said undulating slot or groove. The number of spools or bobbins which may be wound simultaneously is relative to the size of the drum and the size of the wound spools or cheeses and 45 the shape of the guide groove is such that each yarn guide is reciprocated one or more times during each revolution of the drum.

Yarn extends from a reciprocating guide to a 50 spool or bobbin and meets the exterior of the latter adjacent to its point of contact with the drum so that the angle of the yarn between these points does not vary and the tension on the yarn remains constant from the commencement to the completion of winding.

55 But in order that the above and other features

of this invention may be more readily understood, a practical machine constructed in accordance with this invention will now be described with reference to the accompanying drawings in which:—

Fig. 1 is a perspective view of a machine arranged to wind eight cheeses simultaneously.

Fig. 2 is a sectional plan of the grooved drum and adjacent parts.

Fig. 3 is a front elevation of a grooved drum.

Fig. 4 is a detail side elevation showing part of the grooved drum and one of the winding units.

Fig. 5 is a detail plan view of part of the grooved drum and one of the winding units.

Fig. 6 is a detail side elevation showing part of the grooved drum and a winding unit for conical spools or bobbins.

Fig. 7 is a front elevation of a drum having a larger diameter than that shown in Fig. 3.

Fig. 8 is a detail view of roller means engaging the grooved drum.

The machine may be supported on any suitable framework such as a plurality of legs 11 connected by transverse braces 11a. A plate 12 is 25 fixed to the upper ends of the frame uprights 11 and a table 13 is supported above plate 12, by stays 14.

A drum 15 located between the plate 12 and table 13 is fixed on a vertical shaft 16 which 30 may be supported in any suitable manner. Shaft 16 carries a disc 17 the periphery of which contacts with a friction plate 18 that is fixed on a shaft 19 and is revolved by a belt 20 from an electric motor 21. Disc 17 is fixed on shaft 16 35 in any desired position by means of a set screw (not shown). By adjusting the position of disc 17 along shaft 16 relatively to plate 18, the speed of shaft 16 and so of drum 15 may be adjusted to suit the nature of the yarn being wound, the 40 rotation being slower for tender yarn than for tough yarn.

Each stay 14 constitutes a guide rail for a slipper 22 slidably supported thereon. A projection such as a stud 22a extends from each slipper to 45 engage an undulating slot or groove 23 in drum 15. Each said projection 22a may carry an anti-friction roller as 22b (see Fig. 7) of fibre or synthetic resin or other suitable material.

The slot or groove 23 is of such shape that it 50 is adapted to reciprocate each slipper 22 a distance equal to the length of each winding. With a small drum as in Figs. 1 to 3 the shape of the groove will be such that each slipper is reciprocated once during each revolution but with a 55

larger drum the number of reciprocations is increased proportionately thus with a drum three times the size of that shown in Fig. 3 the shape of the groove is such that each slipper will be 5 reciprocated three times during each revolution of the drum (see Fig. 7).

Each slipper 22 carries a yarn guide 24 through which yarn travels from a supply source to a winding spindle.

10 Axles 25 are supported at spaced apart positions around the drum 15 so that an axle is located a suitable distance from each rail 14. Each said axle is adapted to support a spool or bobbin 26 so that its face is parallel with the 15 face of drum 15. When the spool or bobbin is cylindrical (Fig. 4) the axle is vertical and when the spool or bobbin is conical (Fig. 6) the axle is suitably inclined. Yarn from each guide 24 meets the exterior of the associated spool or bobbin at a point adjacent to the point of contact with the drum 15, the angle of feed of the yarn and the distance between the said guide and the point at which the yarn meets the exterior of the spool or bobbin remaining constant, or nearly so.

25 Each axle 25 rises from an angularly shaped lever 28 to which it is fixed at such a position that it may be swung toward or from the drum 15, at will. The inner end of each lever 28 is pivotally connected to the upper face of the plate 30 12 and its outer end 28a constitutes a handle. The pivot pin 29 of each lever 28 extends through the plate 12 and carries a friction element comprising a spring 30 and a tension nut 30a which is adjusted so that lever 28 is held against free 35 movement and so that the exterior of the spool or bobbin 26 or the package associated therewith is yieldingly held against the periphery of the drum 15. As the diameter of the package associated with each axle increases, the axle is moved 40 outwardly and the exterior of the package is held in contact with the drum in such manner that the tension on the yarn remains constant.

Cops as 32 from which yarn is drawn as it is wound are supported on pins which rise from 45 table 13.

A standard 33 which rises from the centre of table 13 carries arms 34 which support suitable yarn guides and tension devices. Each guide comprises a loop 36 and each tension device comprises three rollers 35 supported on pivoted arms 50 35a in such manner that their relative position may be varied to adjust the tension on the yarn being wound.

The diameter of drum 15 determines the speed 55 at which the spools 26 are revolved, and also the rate of travel of the slippers 22. With a small drum up to say one foot in diameter the guide groove 23 is arranged to reciprocate each slipper 22 once in each revolution (see Fig. 3). With a 60 drum of larger diameter the number of reciprocations will increase in approximate ratio thus with a drum three feet in diameter the shape of the guide groove will be such that each slipper is reciprocated three times in each revolution 65 (see Fig. 7). The number of winding units actuated by each drum is governed by the space occupied by such unit and the size of the wound spools or bobbins. A drum about one foot in diameter may actuate eight winding units each adapted to wind a spool or bobbin up to 5 inches 70 in diameter while a drum three feet in diameter may actuate twenty-four winding units and so on.

In operation, yarn from each cop 32 is drawn through a guide 36, around a set of tension rollers 35, under a guide hook 24 and thence to a spool or bobbin 26 about which it is wound in helical layers of constantly changing direction. 5 It will be apparent that by means of levers 28 any spool or bobbin may readily be swung to an inoperative position to enable a break in the yarn to be repaired or a completed spool or bobbin to be removed, without in any way interrupting the winding of other spools or bobbins.

I claim:—

1. In a winding machine, a drum, a vertical shaft supporting said drum, means to rotate said shaft, fixed framing above and below said drum, 15 upright guides fixed at each end to said framing in spaced relationship around said drum, an undulating cam recess in said drum, a reciprocatable slipper on each guide, means on each slipper to engage the said cam, an axle for a winding spool associated with each upright guide, means to support each said axle so that the winding spool supported by it or a package on said spool may be arranged to frictionally contact with the said drum in such manner that the line of contact is parallel with the guide with which it is associated, and a yarn guide on each slipper arranged to direct yarn to a spool or package adjacent to its point of contact with said drum. 25

2. In a winding machine, as claimed in claim 1, 30 means whereby each axle support is pivotally mounted relatively to fixed framing below the drum in such manner that as the diameter of a package about the axle increases, said axle moves in an arcuate path away from the upright guide with which it is associated. 35

3. In a yarn winding machine, as claimed in claim 1, means whereby each axle support is pivotally mounted relatively to fixed framing and 40 friction means arranged relatively to said pivot to hold said support so that it may be displaced when the diameter of the package increases sufficiently to overcome the resistance of said friction means. 45

4. In a yarn winding machine, as claimed in claim 1, an axle support in the form of a bent lever, means whereby said support is pivoted near its bend relatively to fixed framing, friction means arranged about said pivot to contact 50 with an adjacent fixed member and means to adjust the pressure exerted by said friction means whereby the said lever is held in operative position so that it may move when the pressure exerted by the friction means is exceeded by the pressure exerted on a package supported by said axle. 55

5. In a yarn winding machine, as claimed in claim 1, an axle support in the form of a bent lever, means whereby said support is pivoted near its bend relatively to fixed framing, the axle being supported at one end of said lever and the other end of the lever projecting as a handle for control purposes, friction means arranged about said pivot to contact with an adjacent fixed member, and means to adjust the pressure exerted by said friction means whereby the said lever is held in operative position so that it may move when the pressure exerted by the friction means is exceeded by the pressure exerted on a 60 package supported by said axle. 65

WALTER HENRY BOWDEN.
